UNITED STATES PATENT OFFICE.

GEORGE CROSSLAND, OF AMSTERDAM, NEW YORK, ASSIGNOR TO MOHAWK CARPET MILLS, INC., OF AMSTERDAM, NEW YORK, A CORPORATION OF NEW YORK.

SPOOL SUPPORT.

Application filed April 2, 1926. Serial No. 99,373.

The present invention relates to spool carriers for looms used in weaving tufted fabrics, such as Axminster rugs. In spool carriers of this type and tuft yarns are wound on two or more spools carried end to end in bearings mounted on a frame bar which is detachably connected at its ends to a chain carrier. The present invention is directed to a bearing device for the contiguous ends of a pair of such spools, and has for its object to provide a device of simple and strong construction which will firmly support the spools during the movement of the carrier, but which can by a simple manipulation be moved to permit the removal of the spools.

Other objects and features of novelty will be apparent from the following description taken in connection with the drawings, 20 in which,

Fig. 1 is an elevation of a spool carrier mounting three spools, parts being broken away and in section;

Fig. 2 is a cross section on line 2—2 of 25 Fig. 1;

Fig. 3 is an elevational view, partly in section on the line 3—3 of Fig. 2; and

Figs. 4 and 5 are perspective views illustrating the structure for connecting two 30 spools so that they will rotate together.

Referring to the drawings, the beam, or frame, of the device is designated by the numeral 10. It consists of an elongated hollow bar, preferably of metal, of rectangular form in cross section. This bar, as shown, supports three spools 11, 12 and 13. The outer spindles of the two outer spools 11 and 12 are rotatable in bearings formed in the ends of brackets 14 fixed to bar 10, 35 the bearings opening outwardly and the spindles being retained therein by pivoted latches 15, so that the spindles can be moved transversely out of the brackets when the latches are removed.

45 The usual yarn tubes are shown at 16; the devices for holding the carrier on its chain, at 17; and the friction brakes for preventing too rapid rotation of the spools, at 18. The present invention has nothing to do with these parts, so that further reference thereto is unnecessary.

The axial ends, or spindles, of the intermediate spool 13 are mounted respectively in a bearing 19 rigidly secured to beam 10 50 and in a bearing 20 pivoted to the beam on

a transverse axis; and the contiguous ends of the outer spools are non-rotatably connected to the center spool spindles, whereby the three spools are connected for rotation together, but the two outer spools may be withdrawn axially. Any suitable device for thus connecting the spools may be employed. The device illustrated in Figs. 3, 4 and 5 consists of cruciform sockets in the axial ends of the intermediate spool and corresponding projections on the contiguous ends of the two outer spools.

The present invention relates to the construction of the intermediate bearing 20. It will be observed that this bearing is formed in the outer end of an arm 21 which is normally supported parallel with the other bearings, or at right angles to the beam 10. This arm is fulcrumed on a transverse axis so that it is capable of being moved to the dotted line position shown in Fig. 1. In the specific form of the invention shown, arm 21 is pivoted on a pin 22 which passes through the sides of an open box 23 and is riveted or otherwise secured to the sides of beam 10. Box 23 is let into the beam through an opening cut in the wall thereof and fits snugly against the interior walls of said beam, as clearly shown in Fig. 2, the edges of the box at its open side being flush with the surface of the beam. The box thus reinforces the beam at this point, so that the beam is not weakened by cutting out the portion thereof necessary to accommodate the box. Arm 20 extends downwardly from its pivot point and terminates in a foot 24 which engages the bottom of the box 23 when arm 21 is at right angles to the beam and thus prevents inward rotation of the arm beyond this position. The arm is yieldingly held from outward rotation by a stout bow spring 25 which has a reduced end 26 engaging a central longitudinal slot 27 formed in the sole of foot 24 and has its other end also reduced and entered in a slot in box 23. Spring 25 normally holds the foot firmly engaged with the bottom of box 23 with the arm 21 at right angles to beam 10 and the bearing in said arm coaxial with the other 55 bearings.

The spools can be removed simply by unlatching the outer ends of spools 11 and 12 and withdrawing them axially from engagement with spool 13 and then moving 105

55 110

arm 21 against the tension of spring 25 to the dotted line position shown in Fig. 1 and lifting out spool 13, the axial ends of the latter being free from their bearings in this position of arm 21.

Having thus described the invention, what is claimed as new and desired to be secured by Letters Patent is:

1. A spool carrier of the kind described comprising in combination, a pair of co-axial spools rotatably supported at their non-adjacent ends in bearings rigid with the frame of the carrier, a transversely extending two-arm lever fulcrumed to said frame having a bearing in its outer end for the contiguous ends of said spools, the inner end of said lever terminating in a foot engaging a surface of the frame when the bearing in said outer end is coaxial with the other bearings, and a spring exerting pressure on said lever tending to hold said foot against said surface.
2. A spool carrier of the kind described comprising in combination a pair of co-axial spools rotatably supported at their non-adjacent ends in bearings rigid with the frame bar of the carrier, a transversely extending two-arm lever fulcrumed to the carrier having a bearing at its outer end for the contiguous ends of said spools, the inner end of said lever engaging a surface of said frame bar at one side of a plane passing through the fulcrum at right angles to the bar, and a spring acting on said

lower end and tending to hold it in firm engagement with said surface.

3. A spool carrier of the kind described comprising in combination a hollow bar, two bearings fixed thereto, a portion of the wall of said bar between said bearings being cut away, a box open at one side fitted in said bar, a two-arm lever fulcrumed in said box having a bearing in its outer end, the inner arm of said lever terminating in a foot, and a bow spring engaging said foot at one end and said box at the other end and normally holding said foot in firm engagement with said box with the bearing in said lever coaxial with the other bearings.

4. A spool carrier of the kind described comprising in combination a hollow bar substantially rectangular in cross section, two bearings fixed thereto, a portion of the wall of said bar between said bearings being cut away, a substantially rectangular box open at one side secured in said bar with its edges flush with the surface of said bar, a two-arm lever fulcrumed in said box having a bearing in its outer end, the inner arm of said lever terminating in a foot, a bow spring engaging said foot at one end and said box at the other end and normally holding said foot in firm engagement with said box with the bearing in said lever coaxial with the other bearings.

In testimony whereof I hereunto affix my signature.

GEORGE CROSSLAND.
